UNITED STATES PATENT OFFICE.

SHIRLEY L. ELDER, OF HUNTINGTON, WEST VIRGINIA.

SCAFFOLD.

Application filed April 28, 1927. Serial No. 187,305.

This invention relates to scaffolds adapted to position a stage or platform against its work to prevent swinging.

An object of the invention comprehends 5 hanging arms for supporting the platform.

Another object of the invention contemplates means for adjusting a platform upon the hanging arms.

A further object consists of a brace mechanism to assure rigidity of support. 10

More specifically stated the hanging arms are provided with step members.

With the above and other objects in view, the invention further consists of the following 15 novel features and details of construction to be hereinafter more fully described, illustrated in the accompanying drawings and pointed out in the appended claim.

In the drawings:

20 Figure 1 is an elevation of the invention while in use.

Figure 2 is a front elevation thereof.

Figure 3 is a transverse sectional view taken on line 3—3 of Figure 2.

25 Figure 4 is a vertical sectional view taken on line 4—4 of Figure 2.

Figure 5 is a horizontal section taken on line 5—5 of Figure 1.

Referring to the drawings in detail, 30 wherein like characters of reference denote corresponding parts, the reference characters 10 indicate hanging or supporting arms provided with curved ends 11 adapted to be extended over the cornice, ledges, sills and 35 other portions of a building structure suitably anchoring said arms.

Step or tread members 12 are carried at 40 spaced intervals along the lengths of the arms and disposed in staggered relation to accommodate the feet of an operator when ascending or descending upon the arms. A platform or stage such as indicated at 13 is provided with pivoted links 14 upon the opposed sides thereof and upon the bolsters therefor. Clamping sleeves 15 slidably 45 mounted in superimposed relation upon the arms 10 have pivotally mounted between ears carried thereby the adjacent ends of the links 14. Sleeve members 16 slidably 50 mounted upon the arms 10 are held at de-

sired heights thereon by fastening elements passed through openings arranged at spaced intervals in the lengths of the arms. Clamping sleeves 17 are carried by the sleeves 16. Pivoted links 18 intersecting and pivotally connected at intermediate points in their lengths have the outer-most ends thereof pivotally connected with the clamping sleeves 17. Tooth bars 19 carried by the bolsters of the platform or stage 13 are 60 adapted to receive appropriate portions of the upper extremities of the links 18 to space the arms 10 in parallelism with the side of a building to repose the adjacent end of the stage or platform thereagainst to 65 overcome swinging.

When the stage or platform 13 is shifted for an appreciable distance it is to be noted that the normal arrangement of the links 14 and sleeves 15 would tilt the same and to 70 overcome this difficulty the sleeves 15 are reversed from the normal positions.

It is to be noted that the platform and brace mechanism may be raised to a desired height and locked in such position by the 75 aforementioned fastening elements passed through the arms.

The invention is susceptible of various changes in its form, proportions and minor details of construction, and the right is here- 80 reserved to make such changes as properly fall within the scope of the appended claim.

Having described the invention, what is claimed is:

A scaffold comprising vertical arm members 85 provided with curved upper ends adapted to anchor the same upon its work, a platform, sleeve members slidably mounted upon the arms immediately beneath the platform, a pair of vertically spaced clamping sleeves carried by each of the sleeve members, crossed links pivoted together intermediate their ends and having their ends pivoted to the clamping sleeves, and tooth bars depending from the platform and being 90 adapted for engagement with the pivoted links to regulate the platform horizontally 95 of the arms.

In testimony whereof I affix my signature.

SHIRLEY L. ELDER.
